United States Patent Office.

MARGARET J. HAYS, OF ALLEGHENY CITY, PENNSYLVANIA.

Design No. 2,914 dated February 4, 1868.

DESIGN FOR A LABEL.

The Schedule referred to in these Letters Patent and making part of the same.

TO ALL WHOM IT MAY CONCERN:

Be it known that I, MARGARET J. HAYS, of the city and county of Allegheny, in the State of Pennsylvania, have invented a new and useful Design for Label; and I do hereby declare that the following is a full and exact description thereof, reference being had to the accompanying drawing, making part of this specification.

The words and configurations of my improvement in design for label are fully and clearly represented in the accompanying drawing.

What I claim as my invention, and desire to secure by Letters Patent, is—

The design of the label herein described and shown.

MARGARET J. HAYS.
